UNITED STATES PATENT OFFICE.

NORTH DOWLING, OF PHILADELPHIA, PENNSYLVANIA.

PORTABLE FLASH-LIGHT APPARATUS.

1,032,048.

Specification of Letters Patent.

Patented July 9, 1912.

Application filed March 20, 1912. Serial No. 685,109.

To all whom it may concern:

Be it known that I, NORTH DOWLING, a citizen of the United States, residing at the city of Philadelphia, in the county of Philadelphia and State of Pennsylvania, have invented certain new and useful Improvements in Portable Flash-Light Apparatus, of which the following is a specification.

My invention relates to an electrically controlled fuse apparatus for firing powder to produce a flash-light for photographic purposes; and in such connection, my invention has for its principal objects, first, the constructive arrangement of the apparatus; second, the portable telescoping character of the apparatus; third, in conjunction with the telescoping features the convenient and quick adjustments of parts to position, without affecting circuit connections with the fuse point of the apparatus arranged to permit of the firing of powder therefrom; fourth, the provision of the apparatus with means to enable the testing of the circuit before firing the powder, thereby to be assured in advance of the firing of the powder that the apparatus is in required safe condition to fire the powder so as to produce a flash-light therefrom; fifth, the provision of such a portable apparatus with a detachable battery, for furnishing the current for the fuse point adapted to fire the powder; sixth, the provision of such an apparatus with internal separable members as well as an external sectional casing for providing conductors from a battery to the fuse point, in which is included an audible or sight testing device for the circuit prior to actual firing of the powder; and seventh, to the provision of such an apparatus with features and details in constructive arrangement to be hereinafter described and pointed out in the claims.

My invention stated in general terms, consists of a portable electrically actuated as well as controlled flash-light apparatus constructively arranged in substantially the manner hereinafter described and claimed.

The nature and scope of my present invention will be more fully understood from the following description taken in connec-

tion with the accompanying drawings forming part hereof, in which—

Figure 1, is a front elevational view of a portable, telescoping, foldable flash-light apparatus, embodying main features of my said invention. Fig. 2, is a vertical sectional view through the same, showing the detail arrangement of internal members thereof. Fig. 3, is a perspective view enlarged, of the powder container and fuse point located in the bottom thereof, showing one form of fuse point connections therefor. Fig. 4, is a view partly in vertical section through the powder container and fuse point connections of the same, and in broken sectional elevation the standard and internal telescoping members thereof in electrical connection with the fuse point of said container. Fig. 5, is a side elevational view of a broken section of the standard, and in side elevation a detachable battery and signaling device, showing the same in electrical connection with internal and external members of said standard and the electrical connections to a manual operating device. Fig. 6, is a perspective view of one type of a fuse piece, composed of recessed metal pieces having mica between them, for inserting about binding posts of the fuse point of the powder container of Figs. 3 and 4. Fig. 7, is a vertical sectional view through the manual operating device intended to be included in the battery circuit, showing the push-buttons for respectively, testing the said circuit before firing powder of the container from about the fuse point therein; and Fig. 8, is a diagrammatic view of a divided battery circuit in which a buzzer or other signaling device is included and with respectively, push-buttons for testing the device before firing, and for flashing powder from a container, included in said battery circuit.

Referring to the drawings, and particularly Figs. 1 and 2 *a*, is a tubular sectional casing constituting a standard, provided with a series of hinged legs a^1 , connected by means of links a^2 , with a runner a^3 , in order to readily permit of folding the legs against the said standard, when the latter is not in

use. a^4 , is a hollow tubing of less diameter than the said casing and slidably engaging in the said standard a ; and which is adjustably held therein by means of a tightening screw a^5 , extending through a collar secured to the upper end of the casing a , as clearly shown in Fig. 1. a^6 , is another hollow tubing slidably fitting the tubing a^4 , and adapted to be adjustably held thereto by means of a tightening screw a^7 , extending through a collar a^8 , carried thereon, as clearly shown in Fig. 1.

In the lower portion of the hollow standard a , is mounted a fiber or other insulating hollow plug a^9 , as shown in Fig. 2, and in which is mounted a hollow conductor a^{10} , which is securely fitted thereto. The conductor a^{10} , is insulated by means of a surrounding fiber sleeve a^{11} , from the outer casting of the standard a , as clearly shown in Fig. 2. The conductor a^{10} , telescopes with a similar hollow rod a^{12} , the upper end of which is split at a^{13} , and with inturned flanges so as to detachably engage a pear-shaped device a^{14} , of a solid conductor rod a^{15} , which latter is fixed to an insulating fiber plug a^{16} , in the upper section of the standard a .

b , is an insulated adjustable binding post extending through the fiber plug a^9 , into contact with the hollow conductor a^{10} . This binding post is connected with a dry or other suitable battery, by means of an angular-shaped metal seat b^1 , Fig. 5, having an insulated back b^2 , arranged to support a buzzer or other signaling device b^3 , and a suitable dry or other battery b^4 . The signaling device d^3 , is in a divided circuit 11, from the battery b^4 , to a push-button b^8 , extending from a holder b^5 , having leading therefrom a cord b^6 , all to be presently more fully explained, whereby testing of the flash-light appliance can be had before flashing of the powder from the container c , thereof. c , represents a fuse point having binding posts c^1 and c^2 , mounted on a fiber or other suitable insulating base c^4 . These binding posts by metal strips c^5 and c^6 , are respectively connected with the upper section of the standard a , and by an insulated screw-bolt c^7 , with the internal conducting rod a^{15} , as clearly shown in Fig. 2. On the insulating base c^4 , is adapted to be mounted an inclined trough c^8 , in which powder is to be placed directly over the fuse point c , for flashing the same, as will be clearly understood from Fig. 1. The fuse point c , is established by means preferably of a cartridge d , consisting of two recessed pieces of suitable metal d^1 and d^2 , bent over a strip of mica or the like d^3 , and so that the mica is exposed between the said strips or pieces, for example, as clearly shown in Fig. 5, or simply a piece of readily fusible wire, not shown, may be used

and placed in connection with the binding posts c^1 and c^2 , of the fuse point c , in the powder trough c^8 , so that when the current is applied to the cartridge at the fuse point c , the powder will be instantly flashed.

In the head of the push-button device b^5 , is provided a manual push-button b^7 , which when depressed actuates the battery circuit to fire the powder of the container c^8 , and on one side is provided a manual push-button b^8 , which when depressed actuates the buzzer or other signaling device b^3 , to test the device, before firing of the powder for producing a flash-light therefrom.

In Fig. 8, are shown the circuits 10 and 12, from the battery b^4 , to the push-button b^7 , and its contact, and in which circuit 12, is included the binding posts c^1 and c^2 , with the fuse-point c , and at which point the powder is placed, in a container, to be flashed therefrom. From the battery b^4 , the circuit is divided through the buzzer b^3 , to the push-button b^8 , when the line 11, is closed with the line 12, to actuate the buzzer for testing the device, without affecting the circuits 10 and 12, through the binding posts c^1 and c^2 , with the fuse-point c , to fire the powder of the container thereat.

Having thus described the nature and objects of my invention, what I claim as new and desire to secure by Letters Patent is:

1. In a flash-light apparatus, a foldable standard having telescoping internal and external sections arranged in a battery circuit, a powder container having fuse points for a cartridge in said battery circuit and a manually operable circuit closing device for closing the circuit to fire said cartridge in combination with means for testing said circuit adapted to be included in said circuit by the closing of a second manually operable circuit closing device.

2. In a flash-light apparatus, a foldable standard having telescoping internal and external sections arranged in circuit with a battery, a powder container having a fuse point in said battery circuit, a signaling device adapted to be included in circuit from said battery with a circuit closing device for testing said apparatus and a circuit closing device to establish a circuit from said battery with said fuse-point which excludes said signaling device, for firing powder from said container.

3. In a flash-light apparatus, a foldable sectional standard in which certain of the internal members are stationary and others detachable, and one of said internal sectional members insulated from the outer sectional members of said standard, said members arranged in circuit with a battery, a container for powder having a fuse-point provided with binding posts for a detachable cartridge arranged in said battery cir-

cuit, a signaling device adapted to be included in circuit from said battery with a circuit closing device for testing said apparatus and a circuit closing device to establish a circuit from said battery with said fuse-point for firing powder from said container.

In witness whereof, I have hereunto set my signature in the presence of the two subscribing witnesses hereto.

NORTH DOWLING.
